DESIGN FOR A TOY MACHINE GUN

Edmund L. Jahnke, Minneapolis, Minn.

Application September 6, 1943, Serial No. 111,070

Term of patent 3½ years

(Cl. D34—15)

To all whom it may concern:

Be it known that I, Edmund L. Jahnke, a citizen of the United States and residing in the city of Minneapolis, county of Hennepin, and State of Minnesota, have invented a new, original, and ornamental Design for a Toy Machine Gun, of which the following is a specification, reference being had to the accompanying drawing, forming a part thereof, wherein,

Fig. 1 is a plan view of a toy machine gun showing my new design; and

Fig. 2 is a side elevational view thereof.

I claim:

The ornamental design for a toy machine gun, as shown.

EDMUND L. JAHNKE.
